UNITED STATES PATENT OFFICE.

DONALD S. BARROWS, OF ROCHESTER, NEW YORK, ASSIGNOR TO THE T. H. SYMINGTON COMPANY, OF ROCHESTER, NEW YORK, A CORPORATION OF MAINE.

DRAFT-RIGGING.

1,293,300.

Specification of Letters Patent.

Patented Feb. 4, 1919.

Application filed June 30, 1917. Serial No. 177,855.

To all whom it may concern:

Be it known that I, DONALD S. BARROWS, a citizen of the United States, residing at Rochester, in the county of Monroe and 5 State of New York, have invented certain new and useful Improvements in Draft-Rigging; and I do hereby declare the following to be a full, clear, and exact description of the invention, such as will enable 10 others skilled in the art to which it appertains to make and use the same.

The invention relates to the art of railway draft rigging and more particularly to a follower block designed for use with that 15 type of draft rigging, in which one or more of the movable elements are operatively connected to the car coupler by means of a transversely extending key.

The principal object of my invention is 20 to provide a key receiving follower block having its end walls or faces connected by a plurality of webs or flanges so arranged and disposed with reference to the end walls, that the follower block while being comparatively light in weight is nevertheless sufficiently strong to adequately resist all 25 loads to which it may be subjected in service. To this end, the main feature of the invention, broadly stated, comprises a key receiving follower block in which the load placed upon the block in service is transmitted from face to face by a plurality of webs or flanges preferably arranged so as to form a hollow column, the walls of the column 30 extending in the direction of the applied force so as to thereby obtain the greatest strength with the least weight of metal.

There are other features of the invention relating to form and details of construction 35 of the device as will be apparent from the more detailed description of the same when taken in connection with the accompanying drawings which have been chosen to illustrate the invention, and in which:

40 Figure 1 is a top plan view of a portion of a car underframe showing a key connected draft rigging which embodies the invention,

Fig. 2 is a side elevation of one of the follower blocks,

50 Fig. 3 is a transverse vertical section on line 3-3 of Fig. 2, and

Fig. 4 is a top plan view of the follower shown in Fig. 2.

Throughout the specification and drawings like parts are designated by like reference characters.

While I have for convenience illustrated my invention in connection with the key connected draft rigging of the type shown and described in the patent to Wright *et al.*, 60 No. 841,757, it is to be understood that I do not limit my invention to this form of draft rigging.

The numeral 1 designates the car coupler, 65 2, 2 are the draft sills to the inner faces of which by means of the rivets 3 are connected the cheek plates 4. The numeral 5 designates a conventional form of tie casting connected to the inner faces of the draft sills 2 adjacent the inner ends of the 70 cheek castings 4 by the rivets 3a. The draft links 6, 6 which may be employed in place of the equivalent yoke, serve to operatively connect the coupler to the draft rigging, these links are each preferably provided adjacent their opposite ends and on their inner or adjacent faces with inwardly extending bosses or shoulders 7, 7 to provide a larger bearing area at the ends of the links to engage the adjacent edges of the draft keys. 75 The rear end of the coupler shank is adapted to contact normally with the forward face of the front follower 8, the inner or rear face of this follower being adapted to contact with the cushioning mechanism, which 80 may be of the type shown comprising outer and inner coiled springs 9 and 10, respectively. The forward face of the rear follower 11 is adapted to engage the rear end of the cushioning mechanism. 85

In order to operatively connect the draft rigging to the draft sills, a plurality of transversely extending draft keys 12 are provided, the forward key being adapted to extend through aligned slots in the coupler, 90 draft links, cheek plates and draft sills. Likewise, the intermediate and rear keys are each adapted to pass through the adjacent follower and through aligned slots in the draft links, cheek plates and draft sills. 100

Since the followers 8 and 11 are substantially identical except for the slight taper indicated at 13 on the rear follower 11, which taper is provided to enable the sides of the follower block to clear the bosses 7 105 on the adjacent faces of the draft links 6,

- when links provided with bosses are used, it will be only necessary to describe one of these followers. As shown in the detail views of the front follower 8, each follower is preferably provided with a pair of spaced end walls 14, 15, which may be provided on their opposite faces with circular lugs or projections 16 and 17, 17, respectively. The lug 16 may serve as a centering mechanism in connection with the usual aperture in the coupler stem, while the lugs 17 are adapted to serve as centering members for the springs of the cushioning mechanism. The end wall 14 is preferably adapted to conform to the rear end of the coupler stem, while the face 15 may, for example, be extended vertically as shown to enable the same to coöperate with the type of cushioning mechanism here illustrated.
- 10 The end walls or faces 14 and 15 are preferably connected by a plurality of upright webs or flanges 18, 18, which form the side walls of the follower block, these flanges 18 are connected to the respective end walls adjacent the lateral edges thereof and are each provided with an alined key-receiving slot 19. The slots 19 may be, and preferably are, surrounded on the outer faces of the flanges 18 with a reinforcing rib or boss 20. A pair of transversely extending flanges 21, are suitably connected to the end walls 14 and 15 intermediate the said upright flanges 18, 18, these flanges 21 are also preferably connected, respectively, to the upper and lower edges of the said flanges 18.
- 15 The side walls or flanges 18 and the transversely extending flanges 21 form a column which extends from the front to the rear face or wall of the follower block, the said column is, as will be observed, from Fig. 3, preferably substantially rectangular in cross section. The upright walls of the column extending between and 20 bracing the lateral edges of the two end walls, while the transversely extending flanges 21, which form the upper and lower faces or walls of the column, extend from the upper and lower edges of the front face 25 to the points or places on the rear face 14 to the points or places on the rear face 15 where the load is transmitted to or from, as the case may be, the cushioning mechanism.
- 20 The alined slots 19, 19 in the side walls or upright flanges 18 may be connected by a centrally arranged and apertured brace 22, which preferably extends from, and is connected to, the central portions of the front and rear walls 14 and 15, respectively, 30 of the follower block.
- 25 To brace and strengthen them the transversely extending flanges 21, are each preferably provided with a plurality of vertically extending webs 23 which are located intermediate the side walls 18. These webs 35
- 23 extend from the outer faces of the flanges 21 to the portions of the adjacent end wall 15 which project above and below the points of intersection of the same with the said flanges 21. A series of vertically extending flanges 24 may be provided to connect the adjacent faces of the flanges 21 to the opposite sides of the centrally arranged brace 22, the said flanges 24 forming in effect continuations of the flanges 25 or webs 23. Each of the flanges 24 and the adjacent portions in the side walls 18 may be provided with a plurality of alined openings 25; the sides of the said opening are, however, preferably spaced 40 from both the flanges 21 and the upper and lower faces of the brace 22 to prevent the material weakening of the said walls and flanges 24.
- 30 A follower block of the form heretofore described is advantageous in that it presents to compressive stress in service a cross section of generally rectangular form whose walls are so disposed as to resist most effectively and to transmit from face to face 45 of the block, with the least possible chance of distortion, the compressive strains to which the follower is subjected. It will also be perceived that by means of internal and external ribs this rectangular section 50 has been so braced that all possible stresses to which the block may be subjected are adequately resisted by sufficient sections of metal so advantageously arranged that the block, while possessing great strength is 55 comparatively light in weight, and is, moreover, a simple casting both to mold and cast.
- 35 Having now described my invention, although it is to be understood that the foregoing description is merely illustrative of one embodiment of the invention, what I claim and desire to secure by Letters Patent is:
- 40 1. In a draft rigging, the combination 60 with a coupler and cushioning mechanism, of a follower block provided with parallel spaced end walls, a plurality of webs for rigidly uniting said walls, said webs forming a substantially rectangular column which extends between the adjacent faces of said walls, and a centrally arranged apertured brace located intermediate some of said webs and rigidly connected to said end walls.
- 45 2. In a draft rigging, the combination 65 with a coupler and cushioning mechanism, of a follower for said cushioning mechanism, said follower having a pair of spaced end walls, a pair of upright webs extending between and connected to said walls adjacent their lateral edges, and a pair of transversely extending webs extending between and connected to said upright webs and means for connecting said end walls 70
- 50 3. In a draft rigging, the combination 75 with a coupler and cushioning mechanism, of a follower for said cushioning mechanism, said follower having a pair of spaced end walls, a pair of upright webs extending between and connected to said walls adjacent their lateral edges, and a pair of transversely extending webs extending between and connected to said upright webs and means for connecting said end walls 80
- 55 4. In a draft rigging, the combination 85 with a coupler and cushioning mechanism, of a follower for said cushioning mechanism, said follower having a pair of spaced end walls, a pair of upright webs extending between and connected to said walls adjacent their lateral edges, and a pair of transversely extending webs extending between and connected to said upright webs and means for connecting said end walls 90
- 60 5. In a draft rigging, the combination 95 with a coupler and cushioning mechanism, of a follower for said cushioning mechanism, said follower having a pair of spaced end walls, a pair of upright webs extending between and connected to said walls adjacent their lateral edges, and a pair of transversely extending webs extending between and connected to said upright webs and means for connecting said end walls 100
- 65 6. In a draft rigging, the combination 105 with a coupler and cushioning mechanism, of a follower for said cushioning mechanism, said follower having a pair of spaced end walls, a pair of upright webs extending between and connected to said walls adjacent their lateral edges, and a pair of transversely extending webs extending between and connected to said upright webs and means for connecting said end walls 110
- 70 7. In a draft rigging, the combination 115 with a coupler and cushioning mechanism, of a follower for said cushioning mechanism, said follower having a pair of spaced end walls, a pair of upright webs extending between and connected to said walls adjacent their lateral edges, and a pair of transversely extending webs extending between and connected to said upright webs and means for connecting said end walls 120
- 75 8. In a draft rigging, the combination 125 with a coupler and cushioning mechanism, of a follower for said cushioning mechanism, said follower having a pair of spaced end walls, a pair of upright webs extending between and connected to said walls adjacent their lateral edges, and a pair of transversely extending webs extending between and connected to said upright webs and means for connecting said end walls 130

intermediate said upright webs, said upright webs each being provided with a key receiving slot.

3. A follower block for a railway draft rigging comprising end walls, a plurality of webs connecting said walls, said webs being arranged to form a substantially rectangular column, means for reinforcing said column, said means comprising a plurality of flanges extending inwardly from some of the walls of the said column.

4. A follower block for railway draft rigging comprising a pair of end walls, a plurality of upright webs connecting said

walls, a plurality of transverse webs extending between and connected to the said upright webs and to the said end walls, one of said end walls having portions which extend above and below the points of connection of the same with the said transversely extending webs, and a plurality of upright flanges formed on the outer faces of each of the said transversely extending webs and connecting each web to the adjacent portion of the said end wall.

In testimony whereof I affix my signature.

DONALD S. BARROWS.
